INSECTICIDE VAPORIZER

Milton A. Hogan, Ann Arbor, Mich.

Application July 17, 1953, Serial No. 26,027

Term of patent 14 years

(Cl. D31—3)

To all whom it may concern:

Be it known that I, Milton A. Hogan, a citizen of the United States, residing in Ann Arbor, Michigan, have invented a new, original, and ornamental Design for an Insecticide Vaporizer, of which the following is a specification, reference being had to the accompanying drawing, forming a part thereof.

Fig. 1 is a side elevational view of an insecticide vaporizer, showing my new design;

Fig. 2 is a top plan view thereof; and

Fig. 3 is a sectional view taken vertically through the center thereof.

The sides not shown are substantially like the side shown in Fig. 1.

I claim:

The ornamental design for an insecticide vaporizer, as shown and described.
